LIQUID DISCHARGE NOZZLE

Filed Feb. 23, 1927

FIG. 3.

FIG. 6.

Inventor
Harry W. Protzeller
by Arthur Nelson

UNITED STATES PATENT OFFICE

ASSIGNOR, HARRY W. PROTZELLER, OF EAST CHICAGO, INDIANA, AND O. F. JORDAN COMPANY, OF EAST CHICAGO, INDIANA, A CORPORATION OF INDIANA

LIQUID-DISCHARGE NOZZLE

Application filed February 23, 1927 Serial No. 170,295.

This invention relates to improvements in nozzles and it consists of the matters herein-after described and more particularly pointed out in the appended claims.

5 The primary object of the invention is to provide a simple and efficient nozzle, especially adapted for use in rail joint oilers, to form a substantially conical stream which is heavier at diametrically opposite points in one plane than it is at diametrically opposite points in another plane.

A further object of the invention is to provide such a nozzle wherein the valve head has a loose fit on its associated stem or supporting member so that the pressure of the fluid being discharged automatically acts to center the valve head with respect to its associated discharge orifice.

Still another object of the invention is to provide a valve which may be readily adjusted from outside of its casing and while in actual use whereby the stream desired to be produced may be more readily attained, and the integrity thereof maintained.

25 These objects of the invention, as well as others, together with the many advantages thereof, will more fully appear as I proceed with my specification.

In the drawings:

30 Fig. 1 is a view in elevation of a pair of associated nozzles embodying my invention in the relative position they occupy with reference to a rail and the joints thereof when embodied in a rail joint oiler.

35 Fig. 2 is a longitudinal sectional view on an enlarged scale, through one of the nozzles shown in Fig. 1.

Fig. 3 is a transverse vertical section through the same as taken on the line 3—3 of Fig. 2.

Fig. 4 is a view in front elevation of the same.

Fig. 5 is a perspective view of a valve member forming a part of my improved spray nozzle.

Fig. 6 is a diagrammatical view illustrating the cross sectional shape of the conical discharge produced by my improved nozzle.

Referring now in detail to that embodiment of the invention illustrated in the ac-

companying drawings, 1—1 indicate tubular nozzle casings, each closed at its bottom end as by a threaded plug 2 and each made integral with conduits 3—3 in which equal pressures are maintained. Said conduits form parts of a rail joint oiler and when in their normal operative position thereon, they are disposed in vertical planes equally spaced on each side of the rail 4, the abutting ends of the rail sections thereof being connected together by joint or fish plates 5, and bolts 6 in the manner well known. Although the nozzle casings 1—1 are made integral with the conduits or members 3—3 which are connected to a suitable source of spraying fluid under pressure, said nozzle casings are each inclined outwardly from the plane of the associated conduit 3 and as the structure in each casing is the same, a detailed description of one will suffice for both.

Each nozzle casing which is tubular in cross section includes a front wall portion 7 and a rear wall portion 8, the terms "front wall portion" and "rear wall portion" being relative only as to the positions they occupy with respect to the rail. Made integral with and extending at a right angle to the rear wall 8 is a cylindrical boss 9 which has an

interiorly threaded bore 10, therein opening into the interior of the casing 1. In the front wall portion 7 of the nozzle casing and coaxial with the bore 10 is provided an inwardly tapering valve seat like discharge orifice 11, the defining surface of which is radial with respect to a point arranged to the rear of the axis of the nozzle casing.

It is apparent from a comparison of Figs. 2 and 3 that due to the transverse curvature of the front wall portion 7 of the nozzle casing, the length of said orifice in a plane passing through diametrically opposite points in a longitudinal direction with respect to the casing is greater than the length in a plane passing through diametrically opposite points in a transverse direction and at a right angle thereto.

Threaded into the bore 10 and passing coaxially through the orifice 11, is a valve stem 12 in the form of a common headed bolt, a nut 13 being threaded upon the projecting end

of the bolt, with a washer 14 interposed between said nut and the flat end of the boss 9, the nut acting to lock the valve 12 in the desired position with respect to said boss. Loose on said valve 12 is a second valve member 15 as best shown in Figs. 2, 3 and 5 respectively. Said valve member 15 which is tubular includes a head 16 at one end tapered in accordance with the orifice 11 and a cylindrical body 17 at the other end, the junction or meeting portion between said head and body being curved as at 18 so that said portions gradually merge into one another instead of terminating abruptly. Said valve member has an axially disposed bore 19 extending the full length thereof and said bore is of a diameter greater than that of the valve stem 12 so as to fit loosely thereon. When in place upon said valve stem 12, the flat outer end of the head 16 engages against the head of said stem 12 as best shown in Fig. 2. It will be noted from said Fig. 2 that the valve stem 12 has a relatively long threaded bearing in the boss 9 so that when the valve casing is filled with liquid under pressure, it acts equally on both the inside and outside surfaces of the valve member 15 and thus automatically centers said member with respect to the stem 12 and orifice 11. It is also to be noted from Fig. 2 that as the fluid under pressure passes into the inner end of the orifice 11, it is guided thereto by the curved junction part 18 of the member 15 so that said liquid is not broken up into drops but passes thereto as a continuous and unbroken stream, so that when it passes out of said orifice it is not so easily broken up by wind pressure. The amount of space or opening between the valve member head 16 and said orifice may be accurately adjusted by loosening the nut 13 and then turning the stem 12 in the proper direction after which said nut may again be tightened to lock said member in the desired adjusted position.

By the formation of the orifice in the front wall portion of the nozzle casing as before described a differential in radial lengths of the wall or surface defining the orifice is provided and a peculiar condition arises in that the discharging liquid meets with more surface friction and consequently with more resistance at the top and bottom parts of the orifice (considering the longitudinal axis of the nozzle casing) than it does at the sides of said orifice. Thus the liquid stream which issues from said orifice is in the form of a cone and is thinner at the top and bottom than at its sides so that it is of a differential cross sectional form, substantially conforming to a Roman capital "O" as shown in Fig. 6.

Due to the inclination of the nozzle casing, the stream thus formed is directed toward the rail so as to apply more of the fluid upon the bolts and adjacent horizontal portions of the joint plates than upon the bottom and top of

the same. Thus more of the liquid is applied where most needed and less where less needed as upon the rail sections above said plates.

My improved nozzle comprises but a few parts which are readily assembled and which may be made so rugged as to amply withstand the hard service it meets in use. 70

While in describing my invention I have referred to certain details of construction as well as form and arrangement of the parts thereof, I do not wish to be limited thereto except as may be pointed out in the appended claims. 75

I claim as my invention:

1. A liquid discharge nozzle embodying 80
therein a casing having a discharge orifice 85
therein, a valve member extending through 90
said orifice and normally out of engagement 95
therewith, and means providing a rigid support 100
for said member and upon which it is capable 105
of a limited lateral floating movement so as to be centered with respect to said orifice by the pressure of the liquid being discharged.

2. A liquid discharge nozzle embodying 90
therein a casing having a discharge orifice 95
therein, a rigid supporting member positioned 100
coaxially of said orifice and extending therethrough, a valve member loosely engaged 105
on said supporting member and positioned in said orifice so as to center itself with respect to said orifice under the action of the pressure of the liquid being discharged.

3. A liquid discharge nozzle embodying 100
therein a casing having a discharge orifice 105
therein, a rigid supporting member positioned 110
coaxially therewith, a valve member associated 115
with said orifice and having a bore of a diameter larger than said supporting member upon which it is mounted, said valve member being acted upon both inside and outside by the pressure of the liquid discharge 120
and being centered thereby with respect to said orifice.

4. A liquid discharge nozzle embodying 110
therein a casing having a tapered discharge 115
orifice and an interiorly threaded boss diametrically opposite the same, a rigid supporting member threaded into said boss, a valve member positioned on said supporting member and including a tapered head at one end and a tubular body at its other end, said tapered head and tubular body having a bore of such diameter as to permit said valve member to have a limited lateral movement on said supporting member. 120

5. A liquid discharge nozzle embodying a 115
casing having a discharge orifice therein, a 120
valve member extending through said orifice 125
and normally out of engagement therewith, means providing a rigid support for said valve member, said valve member including a tapered head and a substantially cylindrical body extending from the smaller end of said head and connected thereto by a gradually 130

curved portion, said head and body having a tubular bore therein larger in diameter than the diameter of said member upon which it is supported.

⁵ In testimony whereof, I have hereunto set my hand, this 15 day of February, 1927.

HARRY W. PROTZELLER.
